(57) **CLAIM**

(**) Term: **14 Years**

The ornamental design for magnetic field generating device for use in MRI, as shown and described.

(21) Appl. No.: **29/107,120**

DESCRIPTION

(22) Filed: **Jun. 25, 1999**

FIG. 1 is a perspective view of a magnetic field generating device for use in MRI, showing our new design;

(30) **Foreign Application Priority Data**

FIG. 2 is a front view thereof;

Dec. 28, 1998 (JP)	10-38773
Dec. 28, 1998 (JP)	10-38774
